UNITED STATES PATENT OFFICE.

ALFRED WILLIAM BENNIS, OF BOLTON, ENGLAND.

ADJUSTABLE FIRE BRIDGE FOR FURNACES HAVING MOBILE GRATES.

Application filed January 27, 1917. Serial No. 144,994.

(GRANTED UNDER THE PROVISIONS OF THE ACT OF MARCH 3, 1921, 41 STAT. L., 1313.)

To all whom it may concern:

Be it known that I, ALFRED WILLIAM BENNIS, subject of the King of Great Britain, residing at Little Hulton, Bolton, in the county of Lancaster, in the Kingdom of England, have invented certain new and useful Improvements in Adjustable Fire Bridges for Furnaces Having Movable Grates, for which I have filed an application 10 in England, No. 611, January 14, 1916, Patent No. 103,315, January 15, 1917, and of which the following is a specification.

This invention relates to improvements in furnaces of the type in which an adjustable 15 bridge is arranged over a moving grate to allow of clinker, ash and the like refuse to be automatically discharged from the furnace.

According to the present invention, the 20 moving grate extends through or partially through the back wall of the furnace, preferably so that the back shaft and its bearings are outside the furnace.

In certain constructions the grate extends 25 through the bridge wall and a chamber is formed behind the bridge wall so that the operation of removing the clinker either intermittently or continuously by mechanical means can be carried on without stopping 30 the efficient working of the chain grate and the boiler.

Suitable air sealing arrangements are provided to prevent cold air reaching the furnace or to prevent an excess of air reaching 35 the furnace round the adjustable bridge or over the same from the outside.

The invention is more particularly described with reference to the accompanying drawings, in which:—

40 Figure 1 is a side elevation in part section of a pivoted and balanced bridge placed outside a marine type water tube boiler.

Figure 2 is an elevation taken at the left hand side of the furnace—whilst:—

45 Figure 2^a is a transverse section on the right hand side of the furnace.

Figure 3 is a plan view of the furnace.

Now referring to the drawings, in one form of construction as shown in Figures 50 1, 2 and 3, the chain grate extends through the rear wall of a marine boiler furnace part of the rear wall being shown at 9. The chain grate 1 is supported by spaced rollers 4 and revolves over the rear drum 2

mounted on the rear axle 3, which is placed 55 in this case outside the furnace thereby providing easy access to the bearings.

A pivoted bridge 10 is formed of brick-work and suitable metal, the metal being so disposed as to support the refractory brick. 60 The pivoted bridge 10 has pivots 11 which carry the lever or levers 13 which in turn carry the balance weights 14 by means of the hook rod 15. Any other form of lever and balance may be used as convenient, such 65 as a chain, pulley and balance weight, or a chain or rope and winch.

The pivot is supported on a bearing 12 carried on the side frame 21.

The present construction shows the frame 21 going right down to the ground, but it is obvious of course that the bridge might be supported by the chain grate frame 5 itself should it be found desirable. The chain grate frame 5 is shown supported by 75 wheels 6 and rear axle 7.

A hopper 17 is shown designed to carry away the ashes and clinker which fall over the end of the grate into an underground conduit, but it is obvious that small tubs 80 may be placed underneath the end of the grate, or the clinker can be caused to fall into a suitable conveyor or other apparatus designed to mechanically or pneumatically carry away the clinker and ash as it falls 85 over the end of the grate.

Side seals 20 hinged in a suitable manner are provided to prevent excess air leaking 90 round the sides of the pivoted bridge. These are shown hinged but it is obvious there are many ways of pivoting these to effect the desired result.

In order to prevent air leaking in over the top of the pivoted bridge, a swing sealing plate 18 is provided which may be 95 hinged in such a way as to present a close joint all the way along the top, but it is preferred to use a sealing hook as shown in the drawing with a trough 19 which, when filled with sand or the like forms an efficient air seal.

The plate 18 is so weighted and the position of the hinge is so arranged that a slight pressure is exerted against the pivoted bridge to form an efficient seal.

105 The rear wall of the furnace may be arched where the grate goes through it, or may be supported as shown in Figure 1 by

means of an angle plate 8, the lower portion of which may be protected by another plate in case of overheating.

As the grate 1 travels rearwards carrying the clinker and ash with it any cinders or unburnt fuel which remain on top of the clinker, slag and other refuse may be shaved off by the lower portion of the bridge 10 and will then pile up inside the grate forming a seal, and as any air which may leak into the furnace below the bridge 10 will have to pass through the pile of fuel, it will aid combustion instead of merely forming an undesirable air leak.

The whole of the dumping apparatus and the end of the grate may be closed in if desired, from above the seal plate 18 to the ground, and suitable doors arranged to obtain access to the various parts. In this way the boiler would be suitable for use with forced draught.

A bar 22 is placed behind the grate resting in slots or holes formed in the side frames so that if any very large clinkers form on the grate and any difficulty is experienced in getting them off, the attendant may rest a heavy slicer on top of the bar 22 and so facilitate his work in slicing the grate. This bar will also be found useful in slicing the sides of the grate when clinker which sticks to the brick wall of the furnace may be removed.

By having a sight hole at the side of the furnace and a lever brought adjacent thereto from the pivot 11 the attendant may observe the rear part of the fire and adjust the height of the bridge 10 to suit existing conditions. If he has any large lumps of clinker to get rid of momentarily he can raise the bridge 10 until they are passed and then lower it again.

The pivot 11 may be placed in such a position that the horizontal thrust of the clinker or material being carried by the chain grate

will be sufficiently opposite the centre of the pivot 11 so that it will not either raise or lower the bridge 10 by its thrust, or suitable stops or fastenings may be arranged to prevent the bridge from moving. The construction as shown is however preferred as if a large wedge shaped piece of material gets under the bridge it will not cause a jam but merely raise it and pass underneath it.

As the grate 1 travels rearwards carrying the clinker and ash with it, any cinders or unburnt fuel which remain on the top of the clinker, slag and other refuse may be shaved off by the lower portion of the lifting bridge 10 and will then pile up inside the grate forming a seal.

I declare that what I claim is:—

1. A furnace comprising walls, a moving grate extending through the back wall, an adjustable bridge, means guiding the bridge vertically, a swinging plate preventing leakage of air about said bridge, walls partially surrounding the rear portion of the grate and forming an approximately airtight enclosure for the rear end of the furnace.

2. A furnace comprising walls, a moving grate extending through the back wall, an adjustable bridge, means guiding the bridge vertically, a swinging plate preventing leakage of air about said bridge, walls partially surrounding the rear portion of the grate and forming an approximately airtight enclosure for the rear end of the furnace, a trough supporting said swinging plate and a sealing medium in said trough.

In witness whereof, I have hereunto signed my name, in the presence of two subscribing witnesses.

ALFRED WILLIAM BENNIS.
